UNITED STATES PATENT OFFICE

105,144

DESIGN FOR A BIER PIN FOR HEARSES

Earl L. Schofield, Freeport, Ill., assignor to Henn-ney Motor Company, Freeport, Ill., a corporation of Delaware

Application May 17, 1937, Serial No. 69,384

Term of patent 7 years

To all whom it may concern:

Be it known that I, Earl L. Schofield, a citizen of the United States, residing at Freeport, in the county of Stephenson and State of Illinois, have invented a new, original, and ornamental Design for a Bier Pin for Hearses, of which the following is a specification, reference being had to the accompanying drawing, forming part thereof.

In the drawing:

Figure 1 is a side view of a bier pin for hearses embodying the design of my invention, and

Fig. 2 is a top view.

I claim:

The ornamental design for a bier pin for hearses, substantially as shown.

EARL L. SCHOFIELD.
